WRAPPING MACHINE

Joaquin Alemany Lopez, Habana, Cuba

Application July 9, 1929, Serial No. 376,878, and
in Cuba February 22, 1929

3 Claims. (Cl. 91—47)

This invention is directed to an improvement in wrapping machines designed more particularly for enclosing an appropriate number of cigarettes or like articles in a wrapper.

5 In machines of this character, the cigarettes assembled in proper relation and in appropriate number are wrapped by enveloping about the package thus formed a paper wrapper which, through the instrumentalities of the machine, is 10 appropriately folded and the final folds supplied with adhesive, so as to be sealed in position in the final folding act.

An object of the present invention is the provision of means by which the final folds of the 15 wrapper are, prior to being folded into final position, supplied with a suitable adhesive in order that such final folds may be sealed in place incident to and as a result of the folding pressure.

In connection with the means for applying adhesive to the final folds of the wrapper, the invention contemplated adhesive applying elements which are intermittently operated to a position to receive a coating of adhesive and to a position to permit the uniform and regular application 25 of such coating to the appropriate face of the final fold of the wrapper.

The invention is illustrated in the accompanying drawings, in which:

Figure 1 is a view in side elevation of the adhesive applying mechanism.

Figure 2 is a plan view of the same.

Figure 3 is a vertical sectional view through the same, the applicator being shown partly in section.

35 Figure 4 is a section on line 4—4 of Figure 2, the parts being shown in position to apply the adhesive.

Figure 5 is a detail view illustrating the position of the parts immediately preceding the movement of the partly wrapped package into contact with the applicator.

Figure 6 is a perspective view illustrating the relation of the applicator and wrapper during the adhesive applying operation.

45 In wrapping machines of the usual type, the wrapper is delivered in the horizontal path of the package to be wrapped, so that the delivered sheet or wrapper is moved along with the cigarettes in package form and such sheet, by various 50 instrumentalities forming no part of the present invention, is wrapped into package form about the cigarettes. During the wrapping operation, the wrapper reaches the stage in which the wrapping has been completed except the final folds 55 which are disposed at opposite sides of the pack-

age and, prior to being folded into final position, are to be supplied with an adhesive so that in such final fold a sealing completion of the fold will be accomplished.

The present invention deals also with the means 60 for applying the adhesive to the final folds of the wrapper, and this part of the invention is illustrated more particularly in Figures 1 to 6. As understood and as will be plain from Figure 6, the package of cigarettes or like articles, indicated at 41, is completed except for the end folds 42, and the package in this form rests upon a folding support 43 adapted, in the completion of the folding operation, to be elevated by a standard 44 operated by appropriate mechanism of the 70 machine.

The improved applicator includes a shaft 45 mounted in standards 46 rising from the frame of the machine and located in a position above and in alignment with the package in the folded position indicated in Figure 6. The applicator proper includes disks 47 keyed for longitudinally sliding movement in spaced relation on the shaft 45 by keys 48. These disks are permitted a variety of operating positions longitudinally of the 80 shaft through the medium of latches 49 pivotally supported at the center of the shaft and seating in grooves 50 formed in the shaft, the latches bearing against the hubs of the disks and being held in this bearing position by springs 51. 85 The terminals of the latches are formed with offsets 52 having transverse notches 53. Normally, the disks 47 bear against the projections 52 but by depressing the latches, it is apparent that the spacing between the disks may be increased at will.

Each disk 47 is provided with diametrically opposed projecting portions 54, these portions being arranged in pairs and having a linear dimension substantially coextensive with the fold 42 of the 95 package. The projections 54 are recessed at 55, the said recesses extending through the outer free edge of the projection and through the outer face thereof. The applicators proper, in the form of rubber sections 56, are seated in these 100 recesses and secured by an outer plate 57 held by screws or other fastenings 58. The applicators proper, that is the rubber sections 56, extend beyond the free ends of the projections and thus present a somewhat resilient section which is 105 used, as will later appear, to directly apply the adhesive material.

The shaft 45 is intermittently rotated through mechanism more particularly illustrated in Figures 2 and 4. This mechanism includes a wheel 110

59 keyed upon the shaft 45 immediately adjacent one of the uprights 46, this wheel 59 being provided with diametrically opposed pairs of notches 60 adapted to be engaged by a spring-pressed 80 pawl 61 carried by an arm 62 radiating from a wheel 63 loose on the shaft 45 immediately adjacent the wheel 59. The wheel 63 is formed as a pinion 64 in the portion offset from the arm 62 and the teeth of the pinion are engaged by a toothed sector 65 on one end of a lever 66 pivotally supported on an arm 67 projecting from one of the uprights 46. The lever 66 is connected at the end remote from the pinion 64 with a pitman 68 operated by a suitable part of the power 85 mechanism of the machine, whereby the pawl 61 is moved to engage successive notches 60 in the wheel 59 and thereby impart a step-by-step movement to the applicator.

In order that the applicators proper may be 20 suitably positioned and held in such position for operation, means are provided for insuring that the movement of the shaft 45 is correspondingly accurate as to extent of movement and held temporarily in desired position. To this end, the 25 shaft 45 at the end opposite the wheel 59 is provided with a relatively fixed disk 69 formed with opposed pairs of notches 70. A spring-pressed plunger 71, shaped to cooperate with the notches and mounted in a cylinder 72 and carried by the 30 adjacent upright 46, will serve to insure that the shaft, when moved through a quarter revolution, will be temporarily held against further movement during the subsequent operation. Of course, positive movement of the wheel 59 by the 35 mechanism described will serve to overcome the tension of the spring holding the plunger 71 in locking cooperation with the disk 69 to permit the necessary movement of the shaft and applicator.

40 An adhesive tank 73 is supported upon a frame 74 projecting from the uprights 46. A roller 75 is operative on a shaft 76 mounted in the side walls of the tank and provided at one end with a bevel pinion 77 engaged by a bevel pinion 78 carried on a shaft 79 suitably driven from the power mechanism of the machine. A shaft 80 is mounted transverse the tank and a frame including side bars 81 is fixed on said shaft immediately beyond the tank.

50 Mounted in the terminals of the frame bars 81 is a transverse shaft 82 on which, between the frame bars, is mounted transfer rolls 83, the surface of which is appropriately formed for the transfer of the adhesive from the roller 75 to the applicators. The transfer rolls are adjustable longitudinally of the shaft 82 to compensate for adjustment of the applicators, it being understood that the transfer rolls are substantially equal in width to the similar dimensions of the 55 applicators in order to directly apply the adhesive thereto. The transfer rolls are positively driven through the medium of a belt 84 connecting rollers 85 and 86, the first of which is on the terminal of shaft 82 and the second of which is on a sleeve mounted for free rotation on the end of shaft 80, and which sleeve includes a pinion 87 in gear with a pinion 88 fixed on an extension of shaft 76.

60 It is, of course, apparent that the transfer rolls 83 are moved from a position in contact with the roller 75 to a position in which they may be engaged with the applicators proper in the rotation of the disks 47. To secure this result, an arm 89 is extended from one of the frame bars 81 and 65 provided at its outer end with a lateral pin 90

adapted to seat in a U-shaped terminal 91 at the upper end of a bar 92 which is properly reciprocated through the medium of a connection (not shown) with the power means of the machine.

80 A spring 93, secured at one end to a collar 94 fixed on the bar 92, is secured at its opposite end to the pin 91, thus normally holding the arm 89 and bar 92 connected while permitting a limited independent and relatively upward movement of the bar 89 to compensate for contact between the applicators and transfer rolls, as will later appear. The frame carrying the transfer rolls is projected beyond the roll shaft, as at 95, with a transverse terminal bar 96 to increase the rigidity 90 of the transfer roll frame.

95 The roller 75 is, of course, continuously driven and picks up the adhesive 97 in tank 73, and after passing a scraper 98, which wipes off excess adhesive, carries its adhesive coated surface into a position to be engaged by the transfer rolls 83. The movement of bar 92 is timed so that when the applicator is in operative position, the bar 92 will have moved the transfer roll carrying frame so that the transfer rolls are in contact 100 with the roller 75, that is in the positions indicated in Figure 1 of the drawings.

105 It will, of course, be understood that the transfer rolls are positively driven and as the applicator makes its quarter turn as described, the bar 92 is moved downwardly, swinging the frame 81 to a position to dispose the transfer rolls in the position of movement of the particular applicator 110 56. The transfer rolls are held in this position and the applicator is moved to the full quarter turn, during which the free surfaces of the respective applicators move into contact with the positively driven transfer rolls and the adhesive on the surfaces of these rolls is transferred to the 115 free edges of the applicators.

120 It will, of course, be apparent that the path of movement of the applicators varies from the path of movement of the transfer rolls during their applying operation, and under these circumstances, the spring 93 permits the necessary and 125 comparatively small upward movement of the transfer rolls and frame to insure a comparatively free movement of the applicators while at the same time maintaining constant contact between 130 the transfer rolls and the applicators.

135 When the applicator is in operative position, as illustrated in Figure 1, the support 43 for the partially folded package is moved upwardly. The incomplete folds 42 of the wrapper are brought 140 into contact with the immediately overlying applicators which have been previously charged by contact with the transfer rolls 83 with the adhesive. Under the contact between the applicators and incomplete fold, the adhesive of the applicators is transferred to the inner side of such fold, whereupon the partially completed package travels further into the machine to complete the folding operation. This succeeding folding operation may be carried out by any usual or conventional instrumentalities, as it forms no part 145 of the present invention. With the partially completed folds 42 properly supplied with adhesive through the means of the applicators, the final folding operation insures adherence of these folds to the otherwise completed wrapper and the wrapping operation is completed and the wrapper sealed in place.

145 What is claimed to be new is:

1. A gumming mechanism for wrapping machines including an applicator mounted for rota- 150

tive movement and an article support mounted for vertical movement to and from the operative plane of the applicator, the applicator including a shaft, means for advancing the shaft in a step by step movement, and applicating elements slideable on the shaft relative to each other, each of the applicator elements being made up of two sets of diametrically opposed applying surfaces, the adjacent applying surfaces being at right angles to each other.

2. A gumming mechanism for wrapping machines including an applicator mounted for rotative movement and an article support mounted for vertical movement to and from the operative plane of the applicator, the applicator including a shaft, means for advancing the shaft in a step by step movement, applicating elements slideable on the shaft relative to each other, each of the applicator elements being made up of two sets of diametrically opposed applying surfaces, the adjacent applying surfaces being at right angles to

each other, and means whereby the elements may be held in desired relatively spaced relation.

3. A gumming mechanism for wrapping machines including an applicator mounted for rotative movement and an article support mounted for vertical movement to and from the operative plane of the applicator, the applicator including a shaft, means for advancing the shaft in a step by step movement, applicating elements slideable on the shaft relative to each other, each of the applicator elements being made up of two sets of diametrically opposed applying surfaces, the adjacent applying surfaces being at right angles to each other, and means whereby the elements may be held in desired relatively spaced relation, said means including spring-pressed levers mounted on the shaft and passing through the center of the elements, said levers having terminal means to cooperate with the elements for holding the elements in different positions.
